UNITED STATES PATENT OFFICE.

PETER B. WEILER, OF DETROIT, MICHIGAN.

MULTIPLE-FUSE PLUG.

Application filed April 8, 1921. Serial No. 459,672.

To all whom it may concern:

Be it known that I, PETER B. WEILER, citizen of the United States, residing at Detroit, county of Wayne, State of Michigan, have invented a certain new and useful Improvement in Multiple-Fuse Plugs, and declare the following to be a full, clear, and exact description of the same, such as will enable others skilled in the art to which it pertains to make and use the same, reference being had to the accompanying drawings, which form a part of this specification.

The object of my invention is to provide a multiple fuse plug of simple, durable, and inexpensive construction.

A further object is to provide a fuse plug which may be renewed when burnt out by merely turning a button as distinguished from the type of plug with which I am familiar, where it is necessary to replace the plug when the latter is burnt out.

A further object of my invention is to provide such a plug with a plurality of fuse members so that such members may be successively connected into the electrical circuit, and to provide a button which may be turned to change the fuse member which is in use, and which will indicate which of the fuse members have been burnt out.

A further object of my invention is to provide a spider which is composed of fusible material so that the ends of the arms of the spider may be used as the fuse members, and so that the entire set of fuse members may be struck out by a punch press from sheet material at a single operation.

A further object of my invention is to provide a member movable in one direction only and arranged to contact successively with the ends of the fuse members to thereby close the circuit therethrough, said member comprising a spring adapted to form a locking member for the button, a closure member for the circuit, and a latch member to prevent the button from being turned the wrong way so that burnt out fuse members might be thrown into the circuit.

A further object of my invention is to provide a multiple fuse plug which is so arranged that the fusing of one of the fuse members will not damage the remaining unused fuse members.

A further object of my invention is to provide in combination with my improved multiple fuse plug, a member composed of insulating material, adapted to form a com-

bined insulating and separating member, and to form a ratchet device for insuring that the control button will not be turned to connect a burnt out fuse member into the circuit.

With these and other objects in view my invention consists in the arrangement, combination, and construction of the various parts of my improved device, as described in the specification, stated in the objects, and shown in the drawings, in which:

Figure 1 shows a vertical central sectional view through my improved multiple fuse plug.

Figure 2 shows a horizontal sectional view taken on the line 2—2 of Figure 1,

Figure 3 shows a similar view taken on the line 3—3 of Figure 1,

Figure 4 shows a top or plan view of the fuse spider,

Figure 5 shows a top or plan view of the blank from which the circuit closing member is made, and;

Figure 6 shows a top or plan view of the assembled plug.

Referring to the accompanying drawings, I have used the reference numeral 10 to indicate generally the porcelain base of my improved plug, but it will be understood that any other suitable insulating material may be used for this base. The lower portion of this base is designed to receive a metal or other conducting ferrule 11 which is held from longitudinal movement on the base in one direction by a flange 12, and which is held from longitudinal movement in the opposite direction or rotary movement by having one or more edge portions crimped into corresponding recesses in the base at 13. The ferrule 11 is beaded to form threads which may co-act with similar threads formed in a socket member connected into a circuit.

In this connection it is suggested that in ordinary circuits for power, lighting, and other commercial purposes it is customary to include in the circuit a fusible member, called a "fuse plug," so that any unusual surge of current will burn out the fusible member instead of burning out any of the parts of the current consuming devices on the circuit so that the latter will not be damaged by such surges. These fuse plugs are ordinarily arranged in the circuit by connecting an ordinary light socket therein, and then screwing into the light socket a

plug member which has a wire therein connected across the terminals, which is fusible at a predetermined heat so that a predetermined amount of current will melt out the 5 wire and thereby open the circuit.

Where such plugs are used with the single wire, it is necessary to replace the plug with a new one every time the fuse burns out or "blows," and the necessity for such replacements causes considerable inconvenience. It 10 is therefore my intention to provide such a plug with a plurality of fusible elements which are so arranged that they may be conveniently cut into the circuit successively, 15 without it being necessary to replace the plug each time a fuse blows out.

The upper part of the base member has a cylindrical recess formed therein around 20 which is the side wall 14. At the bottom of this recess a shoulder 15 is formed, and in this shoulder are formed a plurality of pockets or recesses 16, each of these pockets being designed to receive one of the 25 fuse elements of my improved plug. Above the shoulder 15, a second shoulder 17 is formed on the inner wall 14 of the base 10, and in this section of wall between the two shoulders the shoulder grooves 18 are 30 formed, which register vertically with the outer ends of the pockets 16, and form continuations thereof.

Received within the recess within the base 10 between the shoulders 15 and 17 is a member of insulating material which I have 35 designated by the reference numeral 19. This member has a cylindrical body portion below which is a contracted portion 20 designed to fit within the walls below the shoulder 15. The top surface of the member 19 has a 40 recess 22 therein concentric with the circumference so that an annular flange 23 is formed at its upper outer edge, this flange having serrations 24 for a purpose which will hereafter be made clear. The main connecting wire 27 passes down through the member 19 through the main body portion thereof from the central part of the recess 22, as 45 is indicated by the dotted lines 26. This wire 27 then passes down through one of the partitions between the pockets 16 in the main body portion 10 to position adjacent to the ferrule 11, where the body portion is 50 exteriorly recessed to form a pocket in which the end of the wire 27 may be soldered at 55 28 to the ferrule 11 to thereby form an electrical connection therewith.

The member 19 may have a rib 29 at one side designed to be received in a groove in the wall 14 to prevent the member 19 from 60 rotating when it is received in the body member.

A multiple fuse member is shown in Figure 4 and designated generally by the reference numeral 30, this member having a 65 substantially circular body portion with a

central opening therein designed to receive the end of a rivet 31 which extends down through the body member 10 to the bottom thereof, where it is upset to hold against a metallic washer 32. The member 19 is recessed at its bottom central portion to receive the head of the rivet 31, and the latter forms a permanent electrical connection between the multiple fuse member and the second end of the circuit into which the 70 fuse is connected. The fuse member has a plurality of arms 33 extended radially therefrom which preferably have a contracted portion 34 designed to determine the point at which the arms will fuse or burn out 75 when the current therethrough reaches a predetermined amount.

The multiple fuse member 30 is adapted to fit into the recess at the top of the body member so that the member 19 may be 80 pressed down over the main portion 30, thereby allowing the arms 33 to extend through the pockets 16, through the grooves 18, and then to be bent over into the lower portions of the serrations 24. The arms are 85 bent at 35 to pass upwardly through the grooves 18, and at 36 to extend over the serrations so that the contracted portions 34 are disposed within the pockets 16, thereby causing the arms to fuse within such pockets, 90 whereby the flash of the fusing will be either confined to one such pocket, or pass up through the corresponding groove 18, and escape through the top of the recess in the body member without coming in contact 95 with the remaining arms to thereby damage them.

For completing the circuit through the arms 33 successively I have provided the brush or wiper 37, which is illustrated in 100 detail in Figure 5, and which is moved by the button 38 extending through the cover member 39 of the body. The brush 37 consists of a blank formed from sheet metal or other conducting material having a main 105 elongated portion perforated at one end and having laterally extending ears at the end adjacent to the perforation. The operating button has an enlarged portion above the cover 39, designed to be grasped by the 110 hand to rotate the button, and an indicating character 40 is formed at one end thereof. The cover 39 also has indicating numerals 41 thereon so that as the button is rotated, the character 40 may point to the 115 characters 41 successively to indicate which of the arms 33 is in contact with the brush 37.

The button 38 has a shank extending 120 through the cover 39 which shank has a contracted portion at the lower end thereof having opposite longitudinal grooves 42 at the lower end thereof, which have recesses 43 at their upper ends. The ears at the 125 ends of the brush 37 are designed to be 130

turned up into the grooves 42 and then to have their ends crimped into the recesses 43, so that the portion 44 of the ears may hold the brush from rotating relative to the button, by their contact with the edges of the grooves 42, and the ends 45 may hold the brush from longitudinal displacement by their contact with the recesses 43. The end of the wire 27 is extended through the perforation in the brush 37, and then upset so that the brush may rotate around the wire, but will form an electrical contact therewith.

From the foregoing it will be seen that the circuit through the plug includes the ferrule 11, wire 27, brush 37, arm 33, portion 30, and the rivet 31. By turning the button 38, the brush 37 may be brought successively into contact with each of the arms 33, so that when one of the arms has been fused, then the brush may be swung around to the next arm. In order to replace a burnt out fuse with my improved plug, the button is rotated a proportionate part of a turn, whereby all the difficulty of replacing the plug of the ordinary type is done away with. In this connection it will be noted the serrations 24 are so arranged that brush 37 can only be rotated in one direction, whereby the position of the button and the indicating characters 40 and 41 show the number of the arms 33 that have been burnt out.

The cover 39 for the plug has an annular downwardly extending flange at its outer edge which engages the outer edge of the wall 14, and which may have a portion thereof crimped into corresponding recesses of the wall 14 to hold the cover from displacement, as is illustrated at 46 in the drawings. There is also a central downwardly extending flange 47 which forms a sleeve around the shank of the button and engages the upper surface of an insulating washer 48, which in turn rests on the upper surfaces of the ears of the brush 37. It will thus be seen that the sleeve 47, washer 48, and ears 45 will prevent the button from coming out of the plug, while at the same time the washer 48 insulates the brush 37 from the button and the cover 39.

In the assembly of my improved plug, the multiple fuse member is first placed in the recess in the body, with the arms 33 extending up through the grooves 18, the member 19 is then placed in the recess, and the arms 33 are bent as at 36 so that their ends extend into the bottoms of the serrations 24. The button 38, cover 39, washer 48, the brush 37, and the wire 27 are then assembled by first upsetting the wire to hold it in the brush 37, then bending the ears into the grooves 42, and then crimping the ends of the ears into the recesses 43. The brush assembly may

then be set into the body and secured in place by crimping the edges of the flange on the body member at 46. The ferrule 11 may then be slipped on and crimped into place at 13, and the end of the wire 27 70 (which will slip down through the member 19 and body 10 when the brush is installed) soldered to the ferrule at 28.

In the practical operation of my improved device, the parts are all assembled into the unit as described, and then the unit may be screwed into the socket, always provided in commercial electrical circuits for the fuse plugs. When so placed, my plug will act as an ordinary plug, until the arm 80 33 which is connected, may be fused or blown by any cause. Then it is only necessary to rotate the button from one of the characters 41 to the next in order to connect in a new arm 33, and thereby reclose the 85 circuit.

The many practical advantages resulting from the use of my improved device have been brought out in the course of this specification, but it may be specially pointed out here that a large amount of time is saved by the use of my improved plug as compared with the use of the ordinary single fuse plug. The time saved by the fact that it is unnecessary to change plugs also adds to the efficiency of the circuit in which my improved plug is used. My plug is also so simply constructed that it has few, if any, more parts than the ordinary single fuse plug, and all of the parts that are used are 100 of such simple construction that they are not likely to get out of order or be broken, but can, if necessary, be readily replaced.

Some changes may be made in the arrangement and construction of the various parts of my improved device without departing from the spirit of the invention therein, and it is my intention to cover by the appended claims such changes as may be reasonably included in the scope thereof. 110

What I claim is:

1. In a device of the class described, a body member having a recess in the top thereof, said recess having shoulders formed in the side walls thereof whereby it is divided into two portions of different diameters, the bottom portion being the smaller, a member of cylindrical cross-section adapted to be received within said recess, the lower portion of said member being contracted to correspond with the portions of the recess and the upper surface of the member having serrations therein, a multiple fuse element comprising a body portion adapted to lay between the cylindrical member and the bottom of the recess and having arms adapted to extend up between the cylindrical member and the side walls of the recess, the ends of said arms being turned over into said serrations, a cover member for said re- 125

cess, a shank journaled therein, a brush mounted on said shank in position to successively enter said serrations and to contact with ends of the arms therein when the shank is rotated, and means for connecting the body of the fuse element and the brush into an electrical circuit.

2. In a device of the class described, the combination of a body member having a cylindrical recess in the top thereof, said recess having an offset portion in the bottom thereof and having pockets formed in said offset portion, a fuse element designed to be received within said recess and having arms extended through said pockets, a second member designed to enter said recess to form a closure member to separate said pockets whereby the fusing of one arm may not injure the remaining arms, and means for selectively closing an electrical circuit through said arms.

3. In a device of the class described, the combination of a body member having a recess in the top thereof, a plurality of fuse elements within said recess, a cover member for said recess, a shank journaled in said cover member, means for closing a circuit through said elements selectively, and means for insulating said shank and cover member from said circuit closing means.

4. In a device of the class described, the combination of a body member having a recess in the top thereof, with a cover, a plurality of fuse elements disposed within the recess, a shank extended through said cover member, a brush connected to said shank to thereby be moved to successively contact with said elements, and combined means for fastening the brush to the shank, and for insulating the brush from the cover member.

5. In a device of the class described, the combination of a body member having a recess therein, with a plurality of fixed fuse elements disposed within the recess, a cover member for the recess, a shank extended through said cover, a brush having ears formed at one end designed to be folded up to engage the shank to fasten the brush to the shank, and a washer of insulating material disposed between said ears and the cover to both insulate the cover from the brush and hold the shank from sliding out of the cover.

6. In a device of the class described, a body member having a recess therein, a plu-

rality of spaced fuse members within said recess, a central terminal in said body, means for connecting said terminal with the fuse members, a movable brush device designed to swing to contact successively with said fuse members, an outside terminal member on said body, and a wire extended from said last terminal to the brush member, the wire being pivotally connected to the brush member at its axis whereby the circuit may be maintained through the brush in any of its positions.

7. In a multiple fuse plug, in combination, a body member having a recess in one end, said recess provided with a plurality of wall pockets, a member arranged within said recess to insulate individual pockets from each other, said member having an edge serrated to correspond with said pockets, a fuse element having a plurality of arms radiating from a common center, individual arms disposed in individual wall pockets of the recess and extending therefrom to be turned over into the corresponding serration of said insulating member, each of said arms having a reduced portion positioned within the pocket, a movable brush member adapted to successively contact with the portion of said arms disposed in said serrations to close the circuit therethrough.

8. In a multiple fuse plug, a body member provided with a plurality of internal wall pockets arranged in an annular series, a centrally disposed contact member, a plurality of fusible contact elements radiating from said center contact member, said fusible contact elements disposed one in each wall pocket, a centrally disposed member in said recess insulating said fusible elements as they are disposed in the wall pockets from one another, each of said fusible elements having a lessened portion disposed within the wall pocket, said centrally disposed member having an upper surface serrated to correspond with said wall pockets, each of said fusible contact elements extending upwardly from its wall pocket to be turned into the corresponding serration of said centrally disposed member, a movable brush arranged to travel over said serration to successively contact with the individual fusible elements.

In testimony whereof, I sign this specification.

PETER B. WEILER
